GAS STOVE

Isaac Vernon Brumbaugh, St. Louis, Mo., assignor
to American Stove Company, St. Louis, Mo.,
a corporation of New Jersey

Application April 3, 1934, Serial No. 718,831

12 Claims. (Cl. 158—115)

This invention relates to improvements in gas stoves and is directed more particularly to that improvement comprising a flashlighter construction for use with the cooking top burners of the 5 stove or range and the particular manner of concealing not only the flashlighter arrangement, but also the gas manifold, the pilot light, and the major portions of the cooking top burners themselves beneath a burner tray which also 10 serves as a medium for catching and retaining food, "boil-overs", or other foreign substances which may fall downwardly through the cooking grate.

One of the objects of the invention is, therefore, the provision of an improved flashlighter construction for the cooking top burners of a gas 15 stove or range.

Another object of the invention is the provision of novel means for supporting the flash tubes of an automatic lighter.

A further object of the invention is the provision of a flashlighter construction for the cooking top burners of a gas stove or range wherein means are provided for assuring proper positioning of the flash tubes in respect to the main burners and the pilot light burner of the range.

A still further object is the provision of means for concealing the flashlighter construction and other stove parts within the cooking top burner chamber and to make said concealing means in the form of a burner tray which will catch and retain dirt, food, "boil-overs" or other foreign substances which may fall downwardly through the cooking top grate of the stove.

Other specific objects and novel features of construction utilized in carrying out the present invention will appear more in detail from the following description when read in the light of the accompanying drawings.

In the drawings:

Figure 1 is a top plan view of the cooking top portion of a gas range having applied thereto the present improved invention.

Fig. 2 is a vertical sectional view through the cooking top portion of the range and the flashlighter equipment, the sections being taken on the line 2—2 of Figure 1.

Fig. 3 is a vertical sectional view taken on the line 3—3 of Fig. 2, looking in the direction indicated by arrow.

Fig. 4 is a top plan view of the cooking top portion of a gas range having applied thereto a modified form of the invention.

Fig. 5 is a vertical sectional view of the cooking

top appearing in Fig. 4 of the drawings, the view being taken on the line 5—5 of Figure 4.

Fig. 6 is a top plan view of the cooking top having applied thereto a still further modification of the present invention.

Fig. 7 is a vertical sectional view of the construction appearing in Fig. 6 of the drawings, the view being taken on the line 7—7 of Figure 6.

Referring now to the drawings and particularly to Figs. 1 and 3 thereof, A designates the burner chamber of the cooking top portion of a gas range and as is usual, the chamber has an open upper end provided with rectangular shaped top frame B. A plurality of burners C are provided within the chamber and as is customary they are 10 positioned within the burner chamber behind the front wall 2 thereof and beneath the top frame B. A series of valve handles 3, exteriorly positioned at the front of the range control a series of valves 4, which in turn control the admission of gas into 15 the mixing tubes 5 of the front burners and 6 of the rear burners.

The burners are illustrated in the drawings as being circular in form, but the shape of the burners can be varied and could be, if desired, 20 of the prong or "star" type or of any other shape that may be desired. The intake manifolds 6 of the rear burners have attachment at 7 with brackets 8 carried by the bowls 9 of the front burners. The mixing tubes 5 of the front burners are supported on the jets 10 of the gas valves and the front ends of the mixing tubes of the rear burners are likewise supported on the jets 10. The rear burners are additionally supported by attachment as at 11 with brackets 12 which extend from the rear wall 13 of the burner chamber.

At a series of points throughout their circumference the bowls of the burners C are provided with outwardly extending spacers 14 having at their lower ends shoulders 15. The purpose of 30 these shouldered spacers will appear hereinafter.

A pilot light D which burns a constant light at its burner tip 16 and is supplied with gas by the pipe 17 is centrally positioned in the burner chamber A and is centrally positioned in respect to the 40 four burners therein. The pilot tip 16 is surrounded by a cup-shaped housing 18.

It is intended that gas delivered to the burner C be automatically lighted by the constant burning light D and to this end there is provided for 45 use in connection with each main burner a flash tube E. By reference to Fig. 3 it will be seen that these tubes are of a U-shape in cross-section and by reference to Figs. 1 and 2 of the drawings that the inner ends 19 of the tubes are notched as at 50 55

20 for supporting connection with the cup-shaped housing 18 surrounding the pilot light burner tip 16. As clearly appears in Fig. 3 of the drawings, this housing 18 is provided with notches 5 20' in its upper end for the reception of the notched inner ends of the flash tubes. This construction prevents longitudinal movement of the flash tubes but still permits the easy and quick detachment of the tubes from the pilot light housing.

The outer ends of the tubes are formed into a ring 21 having a diameter slightly greater than the diameter of the burners C, so that these rings can be moved downwardly over the burners and 15 the burner spacers 14 for support upon the spacer shoulders 15. At the point where the tubes E merge into the rings 21, the tubes have their open outer ends flared as at 22 to receive gas from the lighter ports 23 of the burners so that the gas 20 from the lighter port will enter the tubes and travel towards the pilot flame for ignition. As is well understood a flash or flareback occurs within the lighter tubes E when the gas within them is lighted by the pilot light. This flareback causes 25 the ignition of the gas issuing from the main burner ports 24.

The burner spacers 14 and their shoulders 15 through engagement with the rings 21 of the flash tubes assure proper alignment of the outer flared 30 ends 22 of the tubes with the burners and the interlocking engagement of the inner ends of the tubes with the pilot light housing 18 assures proper positioning and alignment of the inner ends of the tubes with the pilot light flame. Thus 35 the construction is such as to positively insure proper operation of the flash lighter equipment.

The burner tray is indicated at F and is in the form of a rectangular depressed pan having an outwardly extending horizontally disposed upper 40 edge 25 which is supported on the lugs or shoulders 26 carried by the inner edge of the cooking top frame B. This pan is provided in its four corners with openings which are defined by an upwardly extending bead or peripheral edge 27 45 which merges into an upward flare 28 provided in the tray to accommodate the flared outer ends 22 of the flash tubes. The openings in the pan permit the passage of the upper end of the burners and are assured of proper positioning in respect to the burners through the engagement of 50 their beaded edges 27 with the burner spacers 14. The pan is additionally supported by having the beaded edges 27 of the pan openings resting upon the rings 21 of the flash tubes.

55 A flanged opening 29 is provided centrally of the pan and is positioned above the constant burning pilot light. This flanged opening properly positions a pilot light burner cap 30.

A cooking grate or grid is indicated at 31 and it 60 is supported upon the cooking top frame above the burner tray edge 25.

Modifications of Figures 4 and 5

The modification of the invention as illustrated 65 in Figures 4 and 5 resides entirely in the flash lighter tube construction.

In these figures of the drawings the burner chamber contains the same arrangement of burners and the same arrangement of pilot light as 70 is illustrated and described in respect to the preferred form of the invention and likewise the burner tray or burner pan F is constructed just as it is in the preferred form of the invention. As a consequence, with the exception of the flash 75 lighter tube construction, all the parts in Figures

4 and 5 carry the same numerals and letter designations that they do in Figures 1 and 3 of the drawings.

In the preferred construction there were provided individual flash tubes for each burner and each flash tube was supported independent of the other flash tubes and had no connection with them, whereas in the present modification the flash tubes which are designated as H are all made or formed in one piece with the result that 10 their inner ends 40 merge into one another and are thus interconnected so that the four tubes, in plan view, are in the shape of a cross. Just as in connection with the preferred form of the invention, these tubes at their ends are formed into 15 rings 41 which surround the burners and are supported upon the burner spacer shoulder 15 and held in proper spaced relation in respect to the burners by the burner spacers 14. The flash tubes at their outer ends are flared as at 43, as in 20 the preferred form of the invention, but the inner ends of the tubes rather than having slotted connection with the pilot light housing cup 18 have attached to them an open ended collar or tube 44 which telescopes the pilot light burner 25 housing. This telescoping relation assures perfect and proper operative positioning of the inner ends of the tubes in respect to the pilot light burner tip.

In the construction illustrated in this modification all the flash tubes can be quickly and easily removed and replaced as a unit. The structure however is such that the proper positioning of the flash light tubes for proper operation is always assured.

Just as in respect to the preferred form of the invention, the burner tray F is flared at 28 to accommodate the flared outer ends 43 of the flash tubes and likewise the burner tray is provided with the central flanged opening 29 above 40 the pilot light and carrying the pilot light cap 30.

Modifications of Figures 6 and 7

In connection with the further modified form of the invention illustrated in Figures 6 and 7 45 of the drawings, here the same numerals for designating like parts are utilized inasmuch as the burner chamber, pilot light, main burner and burner tray construction is identical with that illustrated and described as the preferred 50 form of the invention.

The modification resides entirely in the construction of the flash tube portion of the automatic burner lighter equipment. In this particular form a center plate K is utilized and 55 has formed in its four corners openings 50 for the reception of the burners C. On its underside the plate carries the flash tubes M which are of a U-shape and have their upper edges 51 welded or otherwise suitably connected to the 60 plate so as to form, in conjunction with the plate, elongated flash tubes. As is true of the preferred form of the invention the outer ends of the tubes are flared as at 52 and the plate is 65 bulged as at 53 to form the enlarged outer tube 70 ends. As is true of the preferred form of the invention, the flash lighter construction is concealed entirely beneath the burner tray and therefore the tray is formed with the bulged portions 28 to accommodate the bulged portions 75 53 of the plate. As is true in respect to the modification appearing in Figures 4 and 5 of the drawings the inner ends of the flash tubes carry a tubular sleeve 54 which telescopes the pilot light cup housing 18 so as to properly position 78

the inner ends of the tubes in operative relation to the pilot light burner tip 16.

The outer ends of the tubes are assured proper operative positioning in respect to the burner pilot light orifices 23 by reason of the burner spacers 14 and the peripheral flanged edge 50' of the openings 50 of the plate are supported upon the burner spacer shoulders 15 and beneath the burner tray just as is true in connection 10 with the other forms of the invention.

The burner tray is provided with the central shouldered opening 29 above the pilot light and carrying the pilot light cap 30. It is readily apparent that the burner tray and the utensil 15 grid are supported just as they are in respect to the other forms of the invention. In respect to this particular modification the central plate K can be quickly removed and replaced with the assurance that the lighter equipment will always 20 be properly operatively positioned in respect to the burners and pilot light.

In connection with this particular form of the invention, just as is true in respect to the other forms, the flash lighter equipment and all of the 25 stove parts within the burner chamber are concealed from view beneath the burner tray and the burner chamber and the stove parts therein are protected by the burner tray, from dirt, food, etc., which may fall downwardly through the 30 cooking or utensil grid 31.

From the foregoing description given in respect to all the forms of the invention, it will be readily apparent that an improved gas range 35 is provided in that the appearance of the range is materially bettered as the burner tray conceals all unsightly parts of the heating and automatic lighting equipment. The structure is such that the tray can be quickly removed for cleaning and the structure is such that the flash tubes 40 of the lighter equipment can be easily and quickly removed to permit access to the burners, the burner valves, the pilot light or the burner chamber in general. The construction is fool proof in that the operator of the stove can remove 45 these parts and be assured that upon replacement of them they will be in proper operative relationship to assure proper operation of the automatic lighter equipment and to permit the proper and unobstructed operation of the main 50 burners. In connection with all forms of the invention the burners themselves extend upwardly through the openings of the burner tray and have their burner orifices 24 positioned above the tray so that the flame and heat from the 55 burners is directed not only against the under side of the utensils upon the cooking grid but with the further advantage that the burner tray serves as a reflecting means for directing the heat from the burners upwardly through the 60 utensil grid and against the under sides of utensils supported thereupon.

It should be apparent that the structure is comparatively cheap and simple of manufacture yet highly desirable by reason of its advantages 65 and that its very simplicity renders it improbable of giving trouble from a maintenance standpoint.

Having thus described my invention what I claim and desire to secure by Letters Patent is:

1. In a gas stove or the like, a cooking top having a burner chamber therebeneath, a main burner and a pilot light burner in said chamber, the main burner provided with a support positioned at a point below the burner orifices, a 70 flash light tube, one end of said tube being posi-

tioned adjacent the pilot light, the other end of the tube terminating adjacent the main burner and being provided with an opening the frame of which encircles said burner and is supported upon the burner support. 5

2. In a gas stove or the like, a cooking top having a burner chamber therebeneath, a plurality of main burners and a pilot light burner in said chamber and arranged in separated relationship, flash light tubes for igniting said main burners 10 from the pilot light burner, means engaging and supporting one end of said tubes to position the same adjacent the flame of the pilot light, the other ends of said tubes being provided with extensions encircling the burners and having a supporting engagement therewith, the parts operating 15 for the purpose described.

3. A structure such as defined in claim 2 where- 20 in the main burners carry spacers, and the flash tube extensions encircle said spacers for properly positioning the upper ends of the tubes in respect to the burners.

4. In a gas stove, a burner chamber, a plurality of main burners therein in separated relationship, a pilot light positioned intermediate said main 25 burners, said main burners carrying spacers and shoulders, flash light tubes for igniting said main burners from the pilot light burner, means engag- 30 ing and supporting the inner ends of said flash light tubes to position the same adjacent the pilot light burner flame, the outer ends of said tubes being provided with an extension forming a framed opening, and the frame of said openings encircling said main burners and the spacers 35 thereof and being supported upon said burner shoulders, the parts operating as and for the purpose described.

5. In a gas stove or the like, a cooking top and a burner chamber therebeneath, main burners located in said chamber in separated relation- 40 ship, a pilot light burner centrally located in respect to said main burners, a member formed in the shape of a cross and carrying flash light tubes at its under side, the inner ends of said tubes in spaced apart relation at the center of 45 said cross, the outer ends of the arms forming said cross being provided with an opening, and the frames of said openings encircling and en- 50 gaging said main burners to support said cross shaped member and to position the outer ends of the tubes adjacent the main burners and the inner separated ends of the tubes radially in re- 55 spect to the pilot light burner.

6. In a gas stove or the like, a cooking top having a burner chamber therebeneath, main burners located in separated relationship within said 55 chamber and provided on their outer walls with shoulders positioned at a point below the plane of the burner orifices, a pilot light approximate- 60 ly centrally located in respect to the main burners, a flash lighter unit comprising a cross shaped member having flash tubes at its under side, the outer ends of the arms forming said member terminating in a framed opening and the inner 65 ends of the tubes terminating short of the center of the cross, and said opening frames embracing the burners and being supported upon the burner shoulders to support the flash tubes in operative position in respect to the burners and pilot light. 70

7. In a gas stove, a cooking top having a burner 75 chamber therebeneath, main burners located in said chamber and provided on their outer walls with supporting shoulders, a plate provided with openings for the reception of said burners and having detachable supporting connection with 75

the shoulders of said burners, flash tubes formed at the under side of said plate and extending radially from the pilot light and terminating at the burner openings of said plate, and the side 5 walls of said burners opposite the tube ends being provided with gas outlet orifices, the parts operating as and for the purpose described.

8. In a gas stove, a cooking top having a burner chamber therebeneath, main burners located in 10 said chamber and provided on their outer walls with spacers and supporting shoulders, a plate provided with openings for the reception of said burners and having detachable supporting connection with the shoulders of said burners, flash 15 tubes formed at the under side of said plate and extending radially from the pilot light and terminating at the burner openings of said plate, and the side walls of said burners opposite the tube ends provided with gas outlet orifices, the parts 20 operating as and for the purpose described.

9. In a gas stove, a cooking top and a burner chamber therebeneath, main burners within said burner chamber and arranged in separated relationship and provided on their outer walls with 25 spacers and supporting shoulders, a plate provided with openings for the reception of said burners and having detachable supporting connection with the shoulders of said burners, a pilot light having a casing, a tubular member carried by the 30 under side of said plate and adapted to telescope said pilot light casing, flash tubes carried at the under side of said plate and extending radially from said tubular member and terminating at the burner openings of said plate, and said burner 35 being provided with gas outlet orifices for the delivery of gas into the adjacent tube ends, the parts operating as and for the purpose described.

10. In a gas stove, a plurality of burners and 40 a pilot light therefor, a plate adapted to embrace said burners and having supporting connection therewith, flash light tubes carried at the under side of said plate, said tubes adapted to have their inner ends positioned adjacent the pilot 45 light burner and their outer ends adjacent the stove main burners, the inner ends of said tubes

having communication with a vertically disposed tubular member, said tubular member adapted to properly position the inner ends of the tubes in respect to the pilot light, and the supporting connection of the plate with the burners properly positioning the outer ends of the tubes in respect to the burners. 5

11. In a gas stove, a plurality of cooking top burners arranged in separated relationship, a pilot light approximately centrally positioned with 10 respect to said burners, a casing for said pilot light having in its side wall cut-out portions having open upper ends, a flash tube for each burner, said flash tubes having extending portions encircling and detachably engaging said burners to 15 support the outer ends of said tubes, said tubes at a point adjacent their inner ends having a portion of reduced size, and the cut-out portions of said pilot light casing telescopically receiving the reduced portions of the tubes to provide a 20 quick detachable interlocking supporting action between the tubes and the pilot casing, for the purpose described.

12. In a gas stove or the like, a cooking top having a plurality of main burners therebeneath 25 and arranged in separated relationship, a pilot light positioned intermediate said burners, flash tubes for igniting said main burners from the pilot light, said main burners at a point below the main burner orifices provided with a 30 gas outlet orifice and a support, said pilot light provided with a casing having in its wall cut-out portions having open upper ends, said flash tubes adjacent their inner ends provided with a portion of reduced size adapted to enter 35 the open upper ends of the cut-out portions to provide quick interlocking detachable supporting action with the pilot light casing, the outer ends of said tubes formed with an extension having therein an opening, and the frame of said extension opening encircling the main burners and having supporting engagement with the aforesaid burner supports, whereby the outer ends of the tubes are properly positioned to receive gas from the aforesaid gas outlet orifices. 40

ISAAC VERNON BRUMBAUGH. 45
